PACKER

Erle P. Halliburton, Los Angeles, Calif., assignor
to Halliburton Oil Well Cementing Company,
Duncan, Okla.

Application March 5, 1937, Serial No. 129,204

2 Claims. (Cl. 166—12)

This invention relates to apparatus adapted for use in oil wells or the like, and more particularly to packers or means for retaining elements in fixed and sealed relation with the casing of an oil well.

It is often desirable, as in the cementing of an oil well, to fix a valve or other structure to a casing. An example of means for this purpose is shown in the patent to Baker, No. 1,035,674, granted August 13, 1912. If it is known prior to the time the casing is placed in the well that a valve is to be needed or used therein, as during a cementing operation, a collar or a shoe may be made up with the casing and may contain the valve. However, it is often desirable to cement wells after the casing has been in place for some time and many other occasions arise where it is desired to fix a valve or the like to a casing while the casing is in the well.

It is an object of the present invention to devise means for securing a device to the casing in the well and which will hold the device firmly and provide a suitable seal between it and the casing.

It is another object of the invention to provide a novel means and method for securing a packer in position in a casing of an oil well.

Another object is to provide a structure which may be easily drilled out and removed from the casing if desired.

Other objects and advantages reside in certain novel features of the arrangement and construction of parts, as will be apparent from the following description taken in connection with the accompanying drawings, in which:

Fig. 1 is a vertical cross-sectional view of a portion of the casing of an oil well with apparatus constructed in accordance with the present invention located therein but not yet fixed thereto.

Fig. 2 is a vertical cross-sectional view of the same apparatus as illustrated in Fig. 1 but illustrating the relative position of the parts after the setting of the packer and slips of the apparatus.

Fig. 3 is a vertical cross-sectional view of a portion of a casing with a device shown in cross-section located therein, the device also being shown in cross-section and illustrating a modified form of invention.

Fig. 4 is a vertical cross-sectional view of a fragment of the apparatus shown in Fig. 3 and showing the position of certain elements after the packer has been set.

Fig. 5 is a plan view of the slips used in the arrangement of Figs. 3 and 4; and

Fig. 6 is an enlarged view of a fragment of the apparatus shown in Figs. 3 and 4 and illustrating the position of the slips while the apparatus is being raised into locking position on the collar of the casing.

Referring to the drawings in detail, and first to the arrangement of Figs. 1 and 2, it will be seen that a casing 11 is there shown as of usual construction. Within the casing the apparatus constructed in accordance with the present invention is located. This apparatus may consist of an inner section of pipe or tubing 12 which it is desired to position and fix to the casing 11. The tubing 12 may contain a valve or other device 121 which it is desired to place at a certain point in the casing 11. Preferably the tubing and the valve, where one is used, are made of cement or aluminum or like material so that they may be easily drilled out in case it is desired to continue drilling operations in the casing after the operations in which the valve is used are completed.

The tubing 12 may be provided with suitable flanges or other means for retaining the valve or other structure but since these may take a variety of shapes they have not been illustrated and it will be understood that the valve or other device may be secured to the tubing 12 in any suitable way.

The main feature of the invention involves the manner in which a packer is set between the tubing 12 and the casing 11. In the arrangement shown in Figs. 1 and 2 the packer is illustrated at 13 and is held in position concentrically around the tubing 12 by means of a pair of retaining rings 14 and 15 the lower one of which may rest upon a shoulder 16 integral with the tubing.

For use as packing material fabric, rubber, or other flexible material may be employed provided the arrangement is such that the packing will bulge out and contact the casing 11 when the retaining rings 14 and 15 are pressed toward each other. The packing material 13 is shown as provided with a number of pockets certain ones of which, as shown at 17, are arranged around the outside of the packing material while another set, such as those shown at 18, are placed on the inside of the packing adjacent the tubing 12. Each of the pockets 17 and 18 is provided with a small tube 19 of cement, glue, adhesive, or other fluid adapted to aid the packing material in sticking to the tubing 12 and the casing 11.

One such suitable cement or adhesive which may be found suitable for this purpose is called "Smooth-On". It is manufactured by the

Smooth-On Manufacturing Company, Jersey City, New Jersey. Other cements may consist of powdered iron oxide treated in such a way as to cause solidification when brought into contact with water. Ordinary Portland cement might be used if treated with known chemicals to cause rapid setting.

It is preferable to use a dry cement or powder which will harden when mixed with water, water almost always being present in a well. It is within the purview of the invention to have some of the tubes 19 filled with water and others with cement, however. Obviously various other known chemicals may be substituted for the cement and water.

The operation of the tubes 19 depends for their operation upon the principle that a tube filled with liquid will not burst so long as the pressure in all directions upon it remains equal, even though the pressure is high. The tubes may be caused to burst, however, by changing their shape, as in flattening them out. Thus, in the arrangement illustrated, when the retaining rings 14 and 15 are moved toward each other the tubes 19 are flattened and burst, thus causing the cement or glue therein to ooze out in contact with the inner and outer surfaces of the packer, the tubing 12 and the casing 11, thus securing the packer thereto.

Some means must be provided for causing the retaining rings 14 and 15 to move toward each other to accomplish the operations mentioned above and in the arrangement of Figs. 1 and 2 the use of slips is illustrated to accomplish this purpose. The slips may also be used to hold the tube 12 against movement in one direction if desired and the construction may be similar to that shown in the Baker patent mentioned above.

In the arrangement illustrated in Figs. 1 and 2 a plurality of slips are employed as shown at 20, these devices consisting merely of segments of cylinders provided with teeth 21 on the outside and with a conical or wedge-shaped inner surface 22. For expanding the slips a truncated conically shaped body 23 is provided so as to engage the inner surfaces 22 of the slips. The body 23 may rest upon the upper retaining ring 15 so that as the tube 12 is raised, pressure will be exerted through the packer upon the cone 23 and cause the slips to expand and to bite into the casing 11. In accordance with known practice, where slips are used it is advisable to employ drag springs, such as those illustrated at 24, to hold the slips against the upward movement until they contact the casing. The drag springs 24 are preferably connected to the slips by means of the links 25.

To lower the apparatus described to the proper point in the casing 11 and to lift the same to expand the packer and set the slips, a mandrel 26 may be used and may be connected to the lower end of drill pipe or the like.

The mandrel 26 is connected to the upper end of the tubing 12 by means of a bayonet joint connector consisting of a plurality of pins 27 on the tube 12 which fit into J-slots 28 in the lower end of the mandrel 26. The mandrel 26 is also preferably provided with a flange element 29 above the upper end of the drag springs 24 to hold the assembly of the cone 23, the slips 20 and the drag springs 24 in position while the apparatus is being lowered into the well.

After the apparatus is set in the well the mandrel 26 may be disconnected therefrom and removed from the well by merely depressing the same slightly and rotating it sufficiently to cause

the pins 27 to enter the longitudinal portion of the J-slots 28.

In the arrangement of Figs. 1 and 2 the casing 11 has been illustrated as consisting of merely a smooth pipe, such as is now commonly employed, in which the sections or stands are welded together instead of using connected collars. Where connecting collars are employed a different embodiment of the invention may be used advantageously and may be constructed as illustrated in Figs. 3 to 6 of the drawings. In these figures two sections or stands of casing are illustrated at 31 and 32 and are joined together by means of a collar 34. Where the sections of casing are joined by means of collars, it is customary to have the sections spaced slightly rather than abut so that they take the position illustrated, leaving an annular space between the ends of the casing and the collar, as illustrated at 35. In accordance with the present invention it is proposed to utilize this annular space and the ends of the sections of casing to secure a valve or other apparatus to the casing and an arrangement for accomplishing this is illustrated in Figs. 3 to 6.

As in Figs. 1 and 2, the apparatus of Figs. 3 to 6 may include the central tubing 37 adapted to have a valve or the like mounted therein and the tubing 37 may have a bayonet joint connection at its upper end like that illustrated in Figs. 1 and 2. In the arrangement shown, however, the arrangement is modified slightly, the mandrel 26' being provided with pins 27' adapted to cooperate with J-slots 28' in the tubing 37. The mandrel is also provided with a shoulder 29' which engages the top of the tubing 37.

The lower end of the tubing 37 is provided with a shoulder 38 which supports a lower retaining ring 39, the packing material 13 which may be identical in construction and operation with the material 13 illustrated in Figs. 1 and 2, and an upper retaining ring 40.

The lower retaining ring 39 may be identical in construction to that illustrated at 14 in Fig. 1 but the upper retaining ring 40 is preferably modified to the extent that it is provided with an upwardly extending flange 41, as shown in the enlargement viewed in Fig. 6, which is adapted to cooperate with the slips 42 as will presently be described.

The slips 42 are similar to those illustrated in Figs. 1 and 2 except that in place of teeth on their outer surface they are provided with an interlocking catch or flanged portions 43 adapted to enter the annular space 35 in the casing mentioned above and interlock with the section of pipe above the collar.

Instead of using a separate conical member to actuate the slips, as in Fig. 1, the tubing 37 may have a portion integral therewith, as illustrated at 44, for actuating the slips, and this portion of the tube 37 is also preferably provided with a flange 45 at its upper end to retain the slips in the proper position, the flange 45 also abutting against the retainer 29' on the mandrel to hold the parts in assembled relation.

The operation of the apparatus is such that as the tube 37 and associated parts are being lowered into the well the slips 42 will take the position illustrated in Fig. 3. The catch portions 43 thereon will be dragging slightly on the casing. When it is desired to set the slips, however, by lifting up upon the mandrel 26' and the tube 37 the conical portion 44 of the tube will contact the upper end of the slips and cause them to rotate outwardly slightly about the fulcrums pro-

vided by the flange 41 of retaining ring 40 (see Fig. 6). The assembled apparatus must be lifted until the catch 43 enters an annular space 35 near a collar 34. When that occurs, further upward movement of the tube 37 will cause the packer to set and the slips to be wedged into place, as illustrated in Fig. 4.

After the cement in the packer has hardened the assembly will be held against downward movement in the casing and the slips 42 will present upward movement therein so that the tube 37 will be fixed firmly to the casing. The mandrel 26' may then be disconnected from the assembly, as before, and removed from the well.

15 It is to be noted that the arrangement is such that the packer in Figs. 3 to 6 cannot be compressed to cause the cement to exude from the tubes therein until the slips have entered the annular space 35. Until the slips enter this space 20 there is nothing tending to force the upper retaining ring 40 downwardly toward the lower retaining ring 39. After the slips are engaging the casing, however, the lower ends abut against the retaining ring 40 and compress the packer as the 25 tube 37 is raised, the final position of the parts being as illustrated in Fig. 4.

The entire apparatus in both of the embodiments of the invention illustrated may be made of material which may be easily drilled out. All

of the metal parts may be made of aluminum or some soft metal or alloy except the slips. The slips are preferably made of cast iron with the teeth or catch-members being case hardened so as to aid them in biting into or engaging the casing and to prevent wear as they are passing through the casing.

5 While only two embodiments of the invention have been shown and described herein, it is obvious that various changes may be made without departing from the spirit of the invention or the scope of the annexed claims.

I claim:

1. An arrangement for securing and sealing an apparatus in the casing of an oil well or the like which includes a packer and means for securing said packer to the casing, said means including sealed containers embedded in said packer and having therein a quantity of a cement of such nature that it hardens and binds the packer to the 15 casing upon mixing with water.

2. A packer adapted for use in an oil well or the like to secure and seal an apparatus to a casing, which consists of a body of flexible material having pockets therein and cement in said pockets, 25 the structure being such that as the flexible material is deformed, the cement will be exuded from said pockets.

ERLE P. HALLIBURTON.
